(57) **CLAIM**

The ornamental design for an archery bow riser as shown and described.

DESCRIPTION

FIG. 1 is an upper perspective view of an archery bow riser embodying the new design;

FIG. 2 is a close up view thereof taken from circle 2 in FIG. 1;

FIG. 3 is a lower perspective view thereof;

FIG. 4 is a close up view thereof taken from circle 4 in FIG. 3;

FIG. 5 is a right side view thereof;

FIG. 6 is a left side view thereof;

FIG. 7 is a front view thereof;

FIG. 8 is a rear view thereof;

FIG. 9 is a top view thereof;

FIG. 10 is a bottom view thereof;

FIG. 11 is a perspective view of an alternative embodiment of the archery bow riser, embodying the new design;

FIG. 12 is a right side view thereof;

FIG. 13 is a left side view thereof;

FIG. 14 is a front view thereof;

FIG. 15 is a rear view thereof;

FIG. 16 is a top view thereof; and,

FIG. 17 is a bottom view thereof.

Features are shown in certain figures in broken lines. The features shown in broken lines do not form any part of the claimed design. Broken lines immediately adjacent the solid-line portions of the design form the boundary of the design, with the broken lines forming no part of the claimed design. Certain figures depict symbolic break lines, immediately adjacent the solid lines, which represent a boundary between claimed and unclaimed subject matter and form no part of the claimed design. The appearance of any portion of the article between the break lines forms no part of the claimed design.
